US0D1034886S

(12) **United States Design Patent** (10) **Patent No.:** **US D1,034,886 S**
(45) **Date of Patent:** **** Jul. 9, 2024**

(54) **ULTRASONIC DOG DRIVER**

(71) Applicant: **Dongguan Caixi Technology Co., Ltd.**,
Dongguan (CN)

(72) Inventor: **Chuxing Lai**, Gaozhou (CN)

(73) Assignee: **Dongguan Caixi Technology Co., Ltd.**,
Dongguan (CN)

(**) Term: **15 Years**

(21) Appl. No.: **29/936,322**

(22) Filed: **Apr. 8, 2024**

(51) LOC (14) Cl. **22-06**

(52) U.S. Cl.

USPC **D22/120; D10/104.1**

(58) **Field of Classification Search**

USPC D22/120, 122; D30/199; D10/104.1,

D10/116.1, 119.1; D13/168

CPC A01K 15/02; A01K 15/021; A01K 15/023;

A01K 15/029
